[57] CLAIM

The ornamental design for a container for display and storage of computer diskettes, as shown and described.

DESCRIPTION

FIG. 1 is a perspective view of a container for display and storage of diskettes showing my new design with a top cover portion in a partially opened position;

FIG. 2 is a front elevational view thereof with the top cover in a closed position;

FIG. 3 is a rear elevational view thereof;

FIG. 4 is a right side elevational view of FIG. 1 with the top cover in the closed position;

FIG. 5 is a left side elevational view thereof;

FIG. 6 is a bottom plan view thereof; and,

FIG. 7 is a top plan view of FIG. 1 with the top cover removed.
